APPARATUS FOR LIFTING AND DISPLACING
RAILROAD RAILS AND FROGS

Antonio Di Biase, Duncannon, Pa.

Application November 22, 1950, Serial No. 197,150

7 Claims. (Cl. 214—1)

1

This invention relates to a novel apparatus of relatively simple construction for lifting and displacing railroad rails and frogs into desired positions in connection with maintenance work of railroads and is primarily intended to save manual labor normally required in such operations and to minimize the need for manually lifting and moving heavy railroad rails and frogs.

More particularly, it is an object of the present invention to provide a pneumatically operated lifting apparatus having skid means whereby a rail or frog supported thereon may be elevated and caused to slide by gravity into a desired position relatively to railroad tracks.

Another object of the invention is to provide a portable apparatus of extremely simple construction capable of being moved to any desired location for use in railroad maintenance work and which may be easily operated manually for supplying air pressure to pneumatic lifting means of the apparatus for accomplishing the lifting and displacing of the rails or frogs.

Still a further object of the invention is to provide an apparatus which is so constructed that it can be connected to and will function with a railroad rail which is secured to railroad ties and for lifting and displacing a rail or frog over said rail.

Various other objects and advantages of the invention will hereinafter become more fully apparent from the following description of the drawings, illustrating a presently preferred embodiment thereof, and wherein:

Figure 1 is a perspective view showing the apparatus in an operative position;

Figure 2 is a side elevational view thereof on a reduced scale;

Figure 3 is a top plan view of the same;

Figure 4 is a front elevational view thereof, taken substantially along a plane as indicated by the line 4—4 of Figure 2;

Figure 5 is an enlarged vertical sectional view taken substantially along a plane as indicated by the line 5—5 of Figure 4;

Figure 6 is a fragmentary vertical sectional view taken substantially along a plane as indicated by the line 6—6 of Figure 3 and on an enlarged scale;

Figure 7 is a fragmentary plan view partly in vertical section, and

Figure 8 is an enlarged fragmentary vertical sectional view taken substantially along a plane as indicated by the line 8—8 of Figure 7.

Referring more specifically to the drawings, the frog or rail lifting and displacing device in its

2

entirety is designated generally 10 and includes an arch-shaped supporting frame, designated generally 11, composed of corresponding arch-shaped sections 12 and 13 each of angular cross section and each including a straight horizontally disposed top portion 14 and a pair of corresponding depending legs 15 which extend downwardly from the ends of the top portion 14 in diverging relationship to one another. The lower ends of the complementary legs 15 of the sections 12 and 13 are secured to a plate 16, which plates form foot members adapted to rest upon the ground and additionally function for supporting the legs 15 in spaced relationship to one another. The legs 15 at each of the frame 11 are also connected adjacent their upper ends by a rigid sleeve 17, for a purpose which will hereinafter become apparent. The two top portions 14 are connected adjacent their ends by plates 18 which combine with the tubes 17 and base plate 16 to maintain the sections 12 and 13 in spaced substantially parallel relationship to provide a slot 19 between the complementary legs 15 of the two sections and a slot 20 between the top portions 14. The foot member 16, sleeve 17 and plates 18 may be permanently secured in any suitable manner as by welding, as indicated at 21, to the sections 12 and 13. The frame 11 also includes a brace leg 22, preferably formed of inverted channel iron the upper end of which is secured in any suitable manner as by welding to the intermediate part of the upper portion of the arch and the lower end of which has a foot member 23 secured thereto and disposed at an oblique angle to the axis of the leg 22 so as to rest flush upon the ground, since said leg 22 is disposed at an oblique angle to a horizontal plane and extends downwardly and rearwardly from the arch portion of the frame, to combine with the legs 15 and foot members 16 to form a tripod support. The frame 11 is likewise provided with a shelf 24 having an inner end secured to the intermediate portion of the arch and the upper end of the leg 22 in any suitable manner. The shelf 24 projects rearwardly from the upper portion of the arch over the leg 22 and is supported substantially in a horizontal plane and at approximately the level of the top of the frame 11 by a brace 25 which extends between and is secured to the outer rear end of the shelf 24 and the lower portion of the brace leg 22.

A pair of angular bearing members 26 is secured to each of the plates 18 in longitudinal alignment relative to the frame and intermediate

of the side edges of said plate, each bearing 26 having an upstanding inner end which is apertured. A ring member 27 is disposed above and spaced from each plate 18 and between the upstanding portions of the bearings 26 thereof and each ring member 27 is provided with aligned trunnions 28 which are journaled in the apertures of the bearings of the plate 18 above which the ring member 27 is disposed for supporting the ring members 27 above the plates 18 for a limited rocking motion relative to the frame 11. As best illustrated in Figure 5, a socket 29 of circular shape is loosely disposed in each ring member 27 and has aligned trunnions 30 projecting outwardly from diametrically opposite portions thereof which are journaled in openings 31 which extend radially through each ring member 27 and which openings 31 are disposed at right angles to the trunnions 28 so that the socket 29 may rock with the ring 27 in which it is mounted and relatively thereto at a right angle to the direction of rocking motion of the ring member. Each socket 29 is provided with an internally threaded upwardly opening recess 32 to receive therein the lower externally threaded end of a cylinder 33 the upper end of which is likewise externally threaded to receive an internally threaded cap 34. A piston 35 is slidably disposed in each cylinder 33 and has a piston rod 36 which extends downwardly therefrom slidably through a stuffing box 37 in the bottom of the socket 29 and loosely through a relatively large opening 38 in the plate 18.

A block 39 is secured to the lower end of each piston rod 36 and has a double headed fastening 40 extending therethrough and loosely through a pair of links 41 for pivotally connecting the links 41 to the block 39 and piston rod 36. A cross beam 42 is disposed parallel to the frame sections 12 and 13 and has spaced portions disposed loosely in the slots 19 between the legs 15. The intermediate portion of the cross beam 42 is preferably reinforced by a channel member 43. The links 41 extend downwardly from the blocks 39 and have their lower ends straddling the cross beam 42 and channel member 43 and the links of each block 39 are connected to the cross beam 42 by a double headed fastening 44 which extends through the cross beam 42 and the channel member 43 and which loosely engages the lower ends of the links 41 and swingably supports the cross beam 42 beneath the blocks 39. A hook, designated generally 45, is pivotally connected to the cross beam 42, one adjacent each end thereof and outwardly of the legs 15, each of said hooks 45 including an angular shank portion including a leg 46 which is pivoted adjacent its terminal by a pivot pin 47 to a side of the cross beam 42 and which leg 46 extends from the pivot 47 in a direction away from the frame 11. The other depending leg 48 of the hook shank terminates at its lower, free end in an inwardly extending hook portion 49, as best illustrated in Figures 1 and 4.

A pair of hand operated pneumatic pumps, each designated generally 50, is supported on the shelf 24 and longitudinally thereof, each of said pumps 50 preferably including a pump cylinder 51 which is suitably fixed to the upper surface of the shelf 24. Each cylinder 51 contains a pump plunger or piston 52 which is slidably mounted therein and which is connected to a piston rod 53 which extends reciprocably through the outer end of the pump cylinder 51 and which is pivotally connected at its exposed outer end

by a pivot 54 to an angular end of a link 55 the opposite end of which is pivotally connected to a lever 56. The lever 56 of each pump 50 is pivotally mounted above its pump cylinder 51 by a bracket 57 which straddles the pump cylinder adjacent its inner end. The links 55 are adapted to be adjustably connected to the levers 56 by pivot pins 58 thereof which selectively engage longitudinally spaced openings 59 in the levers 56. The levers 56 are adapted to be manually engaged at their upper free ends and swung longitudinally of the pump cylinders to reciprocate the pump rods 53 and pistons 52 for expelling air in a conventional manner from the inner ends of the pump cylinders through conduits 60, each including a flexible section 60a. While one form of pump 50 has been disclosed, it will be understood that any conventional type of air pump such as a tire pump may be utilized.

As seen in Figure 8, each socket 29 is provided with a passage 61 having an inlet end 62 to which an end of one of the conduits 60 is connected and into which said conduit end opens. A check valve 63 provided with a spring 64 for normally retaining it in a closed position, permits air to enter the passage 61 through its inlet 62 but prevents the escape of air therefrom. The opposite end of the passage 61 opens into the bottom of the threaded socket 32 below the piston 35 thereof.

The caps 34 of the two cylinders 33 are connected by a conduit 65 having a downwardly offset intermediate portion which is disposed between the lower portions of the cylinders 33 and which includes an outlet branch pipe 66 provided with a check valve 67 adapted to open at a prescribed pressure to release compressed air from the conduit 65. Each vertical leg of the conduit 65 includes a flexible portion 68 to permit the cylinders 33 to have a universal rocking movement relatively to one another, as permitted by the bearings 26 and trunnions 28 and the bearings 31 and trunnions 30.

The apparatus 10 also includes a pair of skids 69 each of which is preferably formed from a short length of railroad rail having an end provided with longitudinally spaced depending bars 70 adapted to loosely straddle the head of a section of a railroad rail 71, as shown in Figures 1, 2 and 3, which is secured in a fixed position in a conventional manner on a number of railroad ties 72 which are in turn supported on a roadbed 73. The skids 69 extend laterally away from the rail 71 in a direction outwardly of the roadbed 73 and are adapted to straddle the frame legs 15. The bills or hook portions 49 of the hooks 45 engage under the head portions of the skids 69 and on the outer sides of said skids so that as the ends of the skids 69 located remote to the rail 71 are elevated the weight thereof will draw the hooks 45 into tighter gripping engagement with the skid heads.

From the foregoing it will be apparent that the frame 11 may be set up in position as illustrated in Figures 1 to 3 at one side of a railroad roadbed and with the skids 69 pivotally engaging the head of the adjacent rail 71 by means of the bars 70 thereof. The hooks 45 are then engaged with the skids 69. A railroad frog or rail 74 is then positioned on the skids 69 and crosswise thereof, adjacent the lower ends of the skids which are disposed adjacent the cross beam 42. By then manually operating the pump levers 56, air may be pumped into the lower ends of jack cylinders 33 so that this air pressure will force the jack pistons 35 upwardly to elevate the ends

of the skids, engaged by the hooks 45, to above the level of the opposite ends of the skids 69 which are pivotally connected to the rail 71, as seen in dotted lines in Figure 2, so that the rail or frog 74 to be positioned on the ties 72 or roadbed 73 to the right of the rail 71, as seen in Figures 2 and 3, may then slide down the skids 69 over the rail 71 and onto the tie 72 between said rail 71 and the rail, not shown, disposed to the right thereof, thus eliminating a large part of the manual labor normally required in lifting and displacing a rail section or frog 74 into position between a pair of railroad rails. As the pistons 35 are moved upwardly by the air pressure therebelow, air in the cylinders 33 above the pistons can escape through the conduit 65 and its blow off valve 67. The pistons 35 have sufficient clearance within the cylinders 33 so that air may escape upwardly past said pistons, but this air escape is insufficient to materially affect the elevation of the pistons to raise the skids 69 from their full line to their dotted line positions of Figure 2 since the air will be pumped into the lower ends of the cylinders much more rapidly than it can escape past the pistons. However, after the frog or rail section 74 slides off of the skids 69 if the pump levers 56 are no longer operated, the weight of the skids 69 and cross beam 42 will urge the pistons 35 downwardly as the air escapes past the pistons to the upper parts of the cylinders 33 so that the device will return to its full line position of Figure 2 and its position of Figure 1 automatically after discharging a frog or rail section 74 therefrom and in a sufficiently short time so that it will be available to receive another frog or rail section on the lower end of the skids 69. The universal rocking movement of the cylinders 33 as previously described, prevents injury to the piston rods in the event of any swinging movement of the cross beam or skids and to accommodate the slight arcuate movement of the cross beam as it is elevated.

The cylinder caps 34 may be provided each with a lubricating fitting 75. For lifting and moving the apparatus 10, a rod 16 is removably inserted through each sleeve 17 so that the apparatus may be conveniently lifted and moved by one man grasping each end of each rod 16.

Various modifications and changes are contemplated and may obviously be resorted to, without departing from the spirit or scope of the invention as hereinafter defined by the appended claims.

I claim as my invention:

1. An apparatus for lifting and displacing railroad rails and frogs comprising a tripod supporting frame, lifting jacks supported on and rising from said frame each including a slidably mounted piston, a piston rod extending downwardly from each piston, a cross beam pivotally supported by and suspended beneath the lower ends of the piston rods, a pair of hooks pivotally connected to the cross beam, one adjacent each end thereof having inwardly and upwardly extending bill portions spaced outwardly with respect to the hook pivots, a pair of skid members having means at corresponding ends thereof adapted to loosely engage the head of a railroad rail for pivotally mounting said skid ends on the railroad rail, each of said skids having a head portion, and said hooks detachably engaging under the head portions of the skids adjacent the

- opposite ends thereof, and means for supplying air under pressure to the lifting jacks below the pistons thereof to elevate the pistons, piston rods, cross beam and the last mentioned ends of the skids to position the last mentioned skid ends above the ends of the skids engaging the railroad rail whereby a section of railroad rail or a frog disposed on the skids will slide down said inclined skids over the railroad rail.
- 5 10 15 20 25 30 35 40 45 50 55 60 65
2. A device as in claim 1, and means providing a universal support for the lower ends of the jack cylinders above the frame for rocking movement of the jack cylinders and piston rods relatively to the frame.
3. A device as in claim 1, said frame including slotted legs in which said cross beam is loosely disposed and by which the cross beam is guided in its vertical movement relatively to the frame.
4. A device as in claim 1, a conduit communicating with and connecting the upper ends of the jack cylinders including flexible sections, and a blow off valve connected to said conduit for releasing air from the cylinders above the pistons.
5. A device as in claim 1, said means for supplying air under pressure to the jack cylinders comprising a pair of manually operated pneumatic pumps and a flexible conduit connecting each of the pumps to one of the jack cylinders.
6. A device as in claim 1, each of said jack cylinders having a pair of trunnions at the lower end thereof, a ring member in which the lower end of the jack cylinder is loosely disposed having bearings in which the jack cylinder trunnions are journaled, a pair of bearings fixed to and rising from the frame between which each of the ring members is disposed, and each ring member having a pair of trunnions journaled in the pair of bearings at a right angle to the trunnions of the jack cylinder whereby each jack cylinder is supported for rocking movement in a plurality of directions relatively to the frame.
7. A lifting and displacing device for railroad rails and frogs comprising a pair of skid members each having an end adapted to be disposed over a fixed railroad rail provided with depending portions loosely straddling the rail head for pivotally mounting the skids thereon, a supporting frame disposed between the opposite, free ends of the skids, a pair of pneumatic jacks, means for supporting said pneumatic jacks on the frame for universal rocking movement relatively thereto, each of said jacks having a reciprocating piston provided with a depending piston rod extending downwardly through the frame, a cross beam loosely mounted in and guided by said frame, means pivotally suspending the cross beam from the lower ends of said piston rods, hooks pivotally connected to the cross beam and detachably engaging the last mentioned ends of the skids, and manually actuated means for supplying air under pressure to the lower ends of the jack cylinders beneath the pistons thereof for elevating the pistons in the jack cylinders to raise the last mentioned ends of said skids to cause a rail section or frog supported thereon to slide by gravity down the skids away from the frame over said rail and the first mentioned ends of the skids engaged thereby.

ANTONIO DI BIASE.
